(57) **CLAIM**

The ornamental design for a shrimp platter having a bottom and a cover, as shown and described.

DESCRIPTION

FIG. 1 is a top perspective view of a shrimp platter; FIG. 2 is an exploded perspective view of the shrimp platter; FIG. 3 is a front elevation view of the shrimp platter; FIG. 4 is a rear elevation view of the shrimp platter; FIG. 5 is a right side elevation view of the shrimp platter; FIG. 6 is a left side elevation view of the shrimp platter; FIG. 7 is a top plan view of the cover portion of the shrimp platter;

FIG. 8 is a bottom plan view of the cover portion of the shrimp platter;

FIG. 9 is a front elevation view of the bottom portion of the shrimp platter;

FIG. 10 is a rear elevation view of the bottom portion of the shrimp platter;

FIG. 11 is a right-side elevation view of the bottom portion of the shrimp platter;

FIG. 12 is a left-side elevation view of the bottom portion of the shrimp platter;

FIG. 13 is a top plan view of the bottom portion of the shrimp platter; and,

FIG. 14 is a bottom plan view of the bottom portion of the shrimp platter.

The broken lines of FIG. 14 show portions of the shrimp platter or environment that form no part of the claimed design.

1 Claim, 8 Drawing Sheets
